PATRICK CALLAHAN, OF BOSTON, MASSACHUSETTS.

SAND-TRAP.

1,070,773.

Specification of Letters Patent. Patented Aug. 19, 1913.

Application filed August 3, 1912. Serial No. 713,165.

To all whom it may concern:

Be it known that I, PATRICK CALLAHAN, a citizen of the United States, residing at Boston, in the county of Suffolk and State 5 of Massachusetts, have invented certain new and useful Improvements in Sand-Traps, of which the following is a specification, reference being had to the accompanying drawings.

10 This invention relates to improvements in traps and particularly to improvements in traps used in drain-pipes of buildings and in the drains which lead to the city-sewers; and an object of this invention is the provision 15 in a trap of the character referred to of means for allowing the free escape of gasolene vapor and the vapors of like volatile substances, which vapors might otherwise and probably would accumulate in the 20 drains and drain-pipes in such quantity as to form with the air and other gases present therein an explosive mixture. Indeed, the ordinances of some cities now require that the owners and operators of garages and 25 like places shall clean the gasolene out of the drains, because of the likelihood of the gasolene forming an explosive mixture as just described. By means of the present invention the necessity for such cleaning 30 (which is very laborious and expensive) is wholly removed.

Another object of this invention is the provision in a trap of the character above mentioned of means for arresting and collecting the sand which is washed into the drain and would otherwise probably accumulate in such quantity as to choke up the sewer, such traps being particularly useful in garages where a large amount of 35 sand flows away with the water used in washing the automobiles.

A third object of this invention is to provide a sand-arresting trap which will be simple in construction, comparatively cheap 45 in manufacture and first cost of installation and efficient, reliable and durable in operation and use.

A fourth object of this invention is to provide a sand-arresting trap in which the 50 water-seal will be maintained unbroken during all the operations necessary in connection therewith, such as removing the sand-collecting pail or the street-grating with its attached dip-pipe.

55 A fifth object of this invention is to pro-

vide a trap which will at one and the same time serve as a stench-trap and a sand-collecting trap.

A sixth object of this invention is the provision of a sand-collecting trap which will require the services of no skilled mechanic, such as a plumber, but which will be susceptible of ready operation and cleaning by the unskilled labor commonly employed at garages and like places.

In the drawings illustrating the principle of this invention and the best mode now known to me of applying that principle, Figure 1 is a central vertical section through my new trap and the waste-pipe leading 70 therfrom; Fig. 2 is a plan view of my new trap, the street-grating being shown removed; and Fig. 3 is a detail showing in elevation the pail in which the sand is caught.

In the top of the box or casing *a* is fitted a suitable grating or perforated cover *b* to the lower face of which is fastened, as by being formed integral therewith, the frusto-conical or funnel-shaped dip-pipe *d*, 80 the lower free end of which projects into the upper end or mouth of the sand-collecting pail *e*. Near its top the latter is formed with an outwardly-projecting flange or band *f* which rests, when the pail is in position, upon the inwardly-projecting flange or ledge *g* which is formed upon the interior of the shell *a* near the top thereof but below the grating *b*. The pail *e* is provided with a suitable bail or handle *h* and, 85 just below its supporting flange or ring *f* it is further formed with a horizontal series of overflow holes *i*. The inner free (or outlet) end of the dip-pipe *d* projects below this series of holes *i* and between the upper 90 portion of the pail *e* and the dip-pipe *d* there is an air-space or chamber *m* which is in free communication with the outer air through the horizontal series of holes *d'* formed in the top of the dip-pipe *d* and 100 the holes *b'* in the foraminated lid or street-grating *b*. This grating rests upon the rim *e'* of the pail *e* and the part of the lid which forms the top of the chamber *m* is imperforate and, therefore, closes the latter from 105 above. Vapor of gasolene or other volatile substance which flows into the drain may escape therefrom readily; thus, if the vapor rises from the liquid which lies between the pail *e* and the shell *a*, the *v* or *u*

will escape by way of the holes i , d' and b' ; if the vapor rises from the liquid lying between the pail e and the dip-pipe d , it may promptly escape through the holes d' , b' ; while vapor rising from the liquid within the dip-pipe d will flow directly upwardly and out through the holes b' in the lid b . At its bottom the shell or casing a is formed with a suitable outlet j in which fits the lower end of a waste-pipe k , which curves upwardly and extends horizontally away from the shell, as is shown in Fig. 1.

The operation of the trap is as follows: The waste-water enters through the holes b' in the lid or grating b and is guided by the dip-pipe d into the pail e , which thus receives the sand and other solid matter carried in suspension by the water. Since the discharge end of the dip-pipe projects well below the holes i in the pail e , the water which flows through the latter holes into the shell a will be free from the sand and other solid matter carried in suspension, since the latter will settle in the lower part of the pail e . It is to be carefully observed that the sand which settles as a deposit in the pail is not forced therefrom but care is taken to retain the sand therein; that is, the pail or bucket e is a sand-collecting receptacle and the trap is a sand-arresting and sand-separating trap. To remove the bucket e after it has become filled to the desired extent, it is necessary only to raise the grating b by pulling upon the slideable handle b^2 , after which the bucket may be raised by means of its bail h and dumped and then replaced. It is to be noted that, when the bucket is in position, it is so firmly set or fixed in position that it cannot be inadvertently or accidentally displaced. In these operations of removing, dumping and replacing the bucket e , no skilled labor, such as that of a plumber, is needed; but the ordinary unskilled help commonly employed at garages will be found capable of doing this simple work. It is further to be carefully observed that the sewer-gas is kept out of the building at all times irrespective of whether the bucket be in place or not; that is, the trap acts as an efficient stench-trap as well as a sand-retaining trap. Why this is will be readily gathered from an inspection of Fig. 1; the sealing water is at all times present and is of sufficiently great depth to constitute under all circumstances an efficient seal. Any gasoline or like volatile oil carried into the trap with the wash-water will float upon the surface of the water in the trap and will evaporate and escape as vapor through the holes i , d' and b' , as hereinbefore explained, whereby the labor and expense of cleaning out the drains and sewers will be obviated and the danger of an explosion due to the formation of a combustible mixture of gasoline vapor and

air in the sewer is avoided. Since only that part of the cover b which lies above the dip-pipe d is foraminated, all the water must enter the trap through the latter, whereby a substantially total separation and collection of the sand in and by the bucket e results. The waste-pipe k lies wholly below the level or plane of the overflow holes i in the bucket e , from which it follows that no backflow of the water will take place through these holes and they are always open for the backflow or escape of the vapor which rises from the volatile hydrocarbon oil floating upon the liquid in the shell or box-like casing a .

I claim:

1. A sand collecting trap comprising a shell provided at its top with a perforated cover and an outlet at its bottom, a bucket mounted within said shell and having its brim in close contact with said perforated cover, said bucket being formed with perforations near its top to permit the flow of water into the shell and the flow of vapor from the same, and a dip-pipe depending from said cover into the mouth of said bucket and formed with perforations near its upper end for the passage of vapor from the upper part of the bucket into the dip-pipe and thence through the perforations in the cover into the outer air, the perforations in the cover being all within the upper edge of the dip-pipe and the remaining portion of the cover being imperforate.

2. A sand collecting trap comprising a shell provided at its top with a perforated cover and an outlet at its bottom, a bucket mounted within said shell and having its brim in close contact with said perforated cover, said bucket being formed with perforations near its top to permit the flow of water into the shell and the flow of vapor from the same, said bucket being of comparatively great depth and being thereby adapted to separate and retain sand and other solid matter carried in suspension by the water entering the perforated cover, and a dip-pipe depending from said cover into the mouth of said bucket and formed with perforations near its upper end for the passage of vapor from the upper part of the bucket into the dip-pipe and thence through the perforations in the cover into the outer air, the perforations in the cover being all within the upper edge of the dip-pipe and the remaining portion of the cover being imperforate, and a waste pipe which extends upwardly from said outlet and which lies below the level of the perforations in said bucket.

3. A sand-collecting trap having a shell provided with a grating at its top and formed with an outlet at its bottom and with a flange which projects inwardly from its side-wall near the top thereof; a sand-col-

lecting pail which is sufficiently deep to separate and retain sand and other solid matter carried in suspension by the water entering through said grating and which is formed near its upper end with an outwardly-projecting flange that rests upon the first-named flange and with overflow holes below said flanges; a dip-pipe the lower end of which extends into the mouth of said 10 pail below said overflow holes, and a waste-pipe which extends upwardly from said out-

let and which lies wholly below the level of the holes in said pail.

Signed at Boston, Suffolk county, Massachusetts, this thirty-first day of July, 1912, 15 in the presence of the two undersigned witnesses.

PATRICK CALLAHAN.
